(57) **CLAIM**

The ornamental design for a wall-mountable combined air freshener and dispenser for thread or ribbon-like products, as shown and described.

DESCRIPTION

FIG. 1 is a top, front, and right side perspective view of a wall-mountable combined air freshener and dispenser for thread or ribbon-like products showing my new design in an uncompressed state;

FIG. 2 is a top, front, and right side perspective view thereof in a compressed state;

FIG. 3 is a top, rear, and right side perspective view thereof in an umcompressed state;

FIG. 4 is a top, rear, and right side perspective view thereof in a compressed state;

FIG. 5 is a top plan view thereof;

FIG. 6 is a left side elevational view thereof;

FIG. 7 is a front elevational view thereof;

FIG. 8 is a rear elevational view thereof;

FIG. 9 is a right side elevational view thereof; and,

FIG. 10 is a rear elevational view thereof.
